CLAIM

The ornamental design for a handle for a spin casting fishing rod, as shown and described.

DESCRIPTION

FIG. 1 is a top plan view of my new handle for a spin casting fishing rod;

FIG. 2 is a left-side elevational view thereof;

FIG. 3 is a bottom plan view thereof;

FIG. 4 is a front elevational view thereof;

FIG. 5 is a rear elevational view thereof;

FIG. 6 is another embodiment of FIG. 1;

FIG. 7 is a left-side elevational view thereof;

FIG. 8 is a bottom plan view thereof;

FIG. 9 is a front elevational view thereof; and

FIG. 10 is a front elevational view thereof.

The right-side elevational view of the embodiment of FIGS. 1-5 is a mirror image of the left-hand elevational view shown in FIG. 2. The right-side elevational view of the embodiment of FIGS. 6-10 is a mirror image of the left-side elevational view of FIG. 7.
